REFRIGERATING APPARATUS

Lawrence A. Philipp, Detroit, Mich., assignor, by
mesne assignments, to Nash-Kelvinator Corporation, Detroit, Mich., a corporation of Maryland

Application April 22, 1935, Serial No. 17,692
Renewed March 3, 1938

2 Claims. (Cl. 62—102)

My invention pertains to refrigerators and particularly to a forced convection refrigerator for household use.

It is an object of my invention to provide a forced convection nonfrosting refrigerator comprising means forming a concentrated cooling zone including a refrigerated freezing section, a finned cooling unit and a motor driven fan mounted above the cooling unit for circulating the air in the compartment over the cooling unit around the freezing section in the cooling zone.

It is also an object of my invention to provide such a refrigerator having a combined freezing chamber and cooling unit mounted in spaced relation adjacent the top wall and one of the side walls of the cabinet having vertically disposed heat conductive fins projecting from the side of the cooling unit adjacent the side wall of the cabinet and a motor driven fan for circulating the air from the upper central portion of the compartment to flow over the cooling unit toward and between the side wall of the compartment and the adjacent fins of the cooling unit.

It is a further object of my invention to provide a refrigerator of the above type comprising a freezing chamber which is mounted in spaced relation adjacent the top wall of the compartment and having a separate cooling unit mounted behind the freezing chamber with an associated motor driven fan for circulating the air in the compartment in heat exchange relation through the cooling unit toward the upper wall of the compartment for deflection around the freezing chamber and uniform distribution around the compartment.

The invention itself, however, both as to its organization and its method of operation, together with additional objects and advantages thereof, will best be understood from the following description of specific embodiments, when read in conjunction with the accompanying drawing, in which:

Fig. 1 is a front elevational view showing a section taken transversely through a forced convection refrigerator arranged in accordance with my invention;

Fig. 2 is a plan sectional view, taken on line II—II of Fig. 3, showing a modified embodiment of my invention; and

Fig. 3 is a vertical sectional view thereof, taken on line III—III of Fig. 2.

Referring more particularly to Fig. 1 of the drawing, the refrigerator consists of a food storage compartment 1 enclosed by a suitable heat insulated cabinet 3 and cooled by a cooling unit

5, which is mounted in the upper portion thereof. The cooling unit comprises an enclosure 7 having freezing plates 9 which are mounted therein in vertically spaced relation for supporting trays for freezing ice cubes or any desired material therein. The freezing shelves 9 are mounted spaced from the side walls of the enclosure 7 and they may comprise either serpentine coils of refrigerant receiving conduit secured to the shelf plates in intimate heat exchange relation therewith or they may comprise flat refrigerant receiving housings which in either form are arranged for receiving vaporizable refrigerant in series parallel relation in a well known manner.

The lower portion of the freezing chamber 7 preferably comprises a cold compartment consisting of a separate enclosure 11 for freezing desserts or other material requiring a lower freezing temperature. The side wall of the combined cooling unit freezing chamber adjacent the side wall of the cabinet is provided with coils 13 of refrigerant receiving conduit which are attached thereto in close coupled thermal relation as by welding or soldering. The outer surface of 25 the same freezing chamber wall supporting coils 13 is provided with vertically disposed heat conductive fins 15 which are secured thereto in spaced relation as by welding or soldering. The refrigerant receiving conduit means within the 30 cooling unit 5 are operatively connected to receive vaporizable liquid refrigerant in series or parallel series arrangement, from any suitable source, as will be readily understood by those skilled in the art.

A small electric motor 17 is mounted on the top wall of the cooling unit 5 in the space between the freezing chamber and the top wall of the cabinet with an air deflecting fan 19 secured on the end of its shaft. The motor 17 may be connected for energization simultaneously with the refrigerant compressor motor or cooling unit or it may be connected directly to the line for continuous operation if desired. The motor drives the fan in a suitable direction for circulating the 45 air from the upper central portion of the compartment over the cooling unit 5. The air is then deflected from the adjacent side wall 20 and is forced downwardly, as indicated by the arrows, and passes through the vertically disposed 50 heat conductive fins 15 projecting from the side wall of the cooling unit. If desired a drip pan 21 may be disposed under the cooling unit.

In accordance with my invention the air in the compartment is thus circulated at a high 55

- velocity through the heat conductive fins around the cooling unit, either continuously or while the refrigerant supply compressor is operated. In this manner the temperature of the air within the food storage compartment is maintained substantially uniform in all positions in the compartment, and the desired degree of refrigeration is obtained from the cooling unit which may be operated at a sufficiently high temperature to avoid freezing the moisture which condenses thereon from the circulating air. Since the moisture is not frozen out of the air in the form of frost, a portion of it returns to the circulating air and its humidity is substantially maintained. The optimum condition for preserving food in the storage compartment is thus substantially maintained and the severe dehydration of the food products is avoided.
- In accordance with the embodiment of my invention disclosed in Figs. 2 and 3, a freezing chamber 25 is mounted in spaced relation from the rear wall 27 of the cabinet providing sufficient space for mounting an open finned cooling unit 29 therebetween. The cooling unit 29 may be supported by brackets 31 on the freezing chamber or any other suitable manner, and it comprises a well known construction of coiled conduit having heat conductive fins. In this embodiment, the air in the compartment is cooled by circulating it through the independent cooling unit, and for the purpose of moving the air therethrough at high velocity a motor driven fan 33 is suspended thereabove from the upper wall of the cabinet. The electric motor 35 may be of any type suitable for driving a fan and it is removably secured to the upper wall 37 of the cabinet by an extension 39 which is inserted above a bracket 41 in the side wall, and a screw clamp 42 which engages a laterally projecting arm 43 extending from the opposite side of the motor frame. The screw clamp projects downwardly from the top wall 37 of the compartment and carries a threaded wing nut 45 by which the motor may be readily clamped in position. In order to complete the energizing connection for the motor 35, two prongs 47 on the motor assembly are plugged into two female sockets 49 in the upper wall 37 of the cabinet. The electric connections may be extended from the sockets through conductors 51 in the cabinet walls to a suitable source of electrical energy. The motor 35 may be energized either continuously, or in parallel with the compressor motor (not shown) for operation simultaneously therewith, as desired. After the air is drawn upwardly through the cooling coils 29 it impinges against the upper wall of the cabinet thus distributing it.

In the embodiment shown in Figs. 2 and 3, the freezing chamber 25 may be of any conventional construction for supporting trays to freeze ice cubes or desserts, and the finned cooling unit may be operatively interconnected with refrigerant expansion coils in the freezing chamber for receiving liquid refrigerant from any suitable source.

It will be seen that I have provided an improved forced convection refrigerator wherein the desired degree of refrigeration is obtained by moving a large volume of air over the cooling surfaces provided in a concentrated cooling zone formed by mounting freezing and cooling means in adjacent spaced relation from the top wall 15 and a side wall or corner of the compartment to be cooled whereby frosting and defrosting are eliminated, and the cooled air is distributed to maintain uniform temperatures throughout the food storage compartment.

5

20

Aside from the specific embodiments of the invention herein shown and described, it will be understood that numerous details of the construction may be altered or omitted without departing from the spirit and scope of the invention as disclosed and claimed, and that I do not desire to limit the invention to the exact constructions herein set forth.

25

I claim as my invention:

1. Refrigerating apparatus comprising a cabinet, an enclosure within said cabinet enclosing a low temperature zone and having a wall exposed to the circulating air in said cabinet for cooling said circulating air, heat absorbing means within the space enclosed by said enclosure and 35 shielded from the direct contact from said circulating air including a portion thermally associated with said wall for cooling the circulating air to the desired temperature and above the prevailing temperature existing within said enclosure, and means for directing the flow of air toward said wall.

40

2. Refrigerating apparatus comprising a cabinet, an enclosure within said cabinet enclosing a low temperature zone, including a wall positioned in close proximity to a wall of the cabinet to provide an air cooling zone, and heat absorbing means including a portion positioned in said low temperature zone for maintaining low temperatures in said low temperature zone and a portion positioned for cooling the circulating air as it passes through said air cooling zone, and a fan for directing the flow of air through said air cooling zone.
